MASSAGE APPARATUS

Carl C. Grund, Des Moines, Iowa

Application March 4, 1955, Serial No. 492,230

13 Claims. (Cl. 128—62)

My invention relates to a new and improved massage apparatus or device and while it was developed primarily for use in massaging the gums, it is equally applicable for use on other parts of the body as will become apparent.

The therapeutic value of massage to body tissues under proper conditions is too well established to require any extensive discussion here although certain aspects should be mentioned for a better understanding of the novel characteristics of my invention as compared with other devices known to the art. In general, massage is a term used to signify a group of external manipulations for the purpose of affecting the nervous and muscular systems and the general circulation. For best results, massage should take the form of compression and release which forces the transudates into the lymph vessels and the red blood cells plugging the capillaries are forced into the venules, thus opening the capillaries to arterial blood. The effect of this is to drain off acids and the injurious end products of inflammation and to bring in fresh oxygen and cell nutriment.

Certain medical and dental texts would point out that massage is more effective when done manually even though there are innumerable devices for doing it mechanically and it has been my experience over a period of many years that the problem lies not in a mechanical apparatus *per se* but in the manner and form of use which seems to be characteristic of such devices. Mechanical massagers for the body and limbs and particularly for use in the treatment of periodontal and gingival disturbances are in what might be termed the vibrator class, or in other words are high speed reciprocating devices that shake or pummel the tissue rather than compress or release it. Consequently, they do not accomplish the blood circulation previously described as the purpose of a proper compression and release massage movement.

It is well established that body tissue has a certain normal resiliency by virtue of which it rebounds from compression of a proper massage movement. As a result when such tissue is subjected to a rapid succession of contacts from a high speed vibrating surface, it may be compressed at the first contact where it remains since successive contacts come at too rapid a rate to permit of any rebounding with the result that the tissue in effect remains static and the intended effect of the purported massage is lost almost entirely. From the above observations it would then appear that the actual nature of the massage movement whether mechanical or manual is itself of minor importance providing it is rhythmical and bears a relationship to the rebounding ability of the tissues and perhaps also to the blood circulation as affected by the pulse rate. Such factors seem to have been completely overlooked by present mechanical massage devices.

It is therefore one of the important objects of this invention to provide a new and improved mechanically operated massaging apparatus characterized by a rhythmical action for compressing and releasing or kneading of the

2

tissue of the body at a rate having a definite relationship to the ability of such tissue to rebound from a compressed position due to its normal resiliency.

Another object of this invention is to provide a massaging device of the above class designed to affect a massage movement at a rate having a definite relationship to the pulse rate.

A still further object of my invention is to provide a gum massaging apparatus constructed to operate at a rate as described above and further constructed so that in use on the gums, it will massage both sides simultaneously, can be adjusted for gums of different widths, and can be regulated to increase or decrease the force and depth of the compression stroke.

Another object of my invention is to provide an improved gum massager for more effective interproximal stimulation in cases of periodontal and gingival disturbances.

These and other objects will be apparent to those skilled in the art.

20 My invention consists in the construction, arrangements, and combination of the various parts of the device, whereby the objects contemplated are attained as hereinafter more fully set forth, specifically pointed out in my claims, and illustrated in the accompanying drawings, in which:

Fig. 1 is a perspective view of my new massaging apparatus illustrating a preferred embodiment thereof for use on gums,

30 Fig. 2 is a side elevational view of the device in Fig. 1 with portions of the casing or housing broken away to more fully illustrate its construction,

Fig. 3 is an enlarged front view of the massaging tips on this device in extreme open position in solid lines, and shown in closed position in broken lines,

35 Fig. 4 is a cross sectional view taken on the line 4—4 of Fig. 5;

Fig. 5 is an enlarged rear view of this device with the cover broken away to more clearly illustrate the construction thereof,

40 Figs. 6 and 7 are rear views of the massaging tips showing them in open and closed position respectively,

Figs. 8 and 9 are enlarged front and side views respectively of one of the massaging tips and shown partially in section to illustrate its attachment to the massaging arm,

Fig. 10 is an enlarged fragmentary view showing calibrations for adjustment of the massage arm and is taken from the line 10—10 in Fig. 2,

50 Fig. 11 is an enlarged top view of the lower portion of the housing in Fig. 2 taken on the line 11—11 of that Fig. 2, and

Fig. 12 is a perspective view of my new massager similar to Fig. 1 but shown adapted and mounted for use on the limbs of the body.

55 Referring to the drawings a casing or housing indicated generally by the numeral 14 which serves also as the handle for this device when adapted for gum massaging is formed with the top 16 and lower 18 sections that are detachably secured together by any suitable means such as the screws 20. The lower section or bottom 18 is in the form of an open topped rectangular receptacle or container having the sides 22 and 24, the rear end 26 and the forward end 28. An elongated tubular support member 30 is mounted through the forward end 28 so that a portion thereof lies within section 18 and is detachably secured therein by a screw 32 inserted from the bottom 34 of section 18 into the underside of member 30. The rearward end 36 of support member 30 (Fig. 2) is thus spaced forwardly of the rear end 26 at a point approximately two thirds the distance from end 28. Thus arranged, member 30 projects forwardly from and beyond

section 18 parallel to the longitudinal axis thereof as shown more particularly in Figs. 1 and 2. In the forward end of tubular member 30 there is inserted a plug-like bearing member 38 (Fig. 3) and a like bearing member 40 is similarly placed in the rear (Figs. 2 and 6). A pair of elongated like rods or shafts 42 and 44 (Fig. 11) designed for rotation about their longitudinal axes as will later appear are mounted in member 30 in horizontal spaced parallel relationship and project from both the forward and rear ends thereof. For this purpose it will be understood that suitable aligned openings are drilled in the respective plugs 38 and 40 and the respective shafts 42 and 44 are rotatable therein and of course are supported thereby. Openings 46 and 48 (Fig. 11) may be provided in the top portion of member 30 within section 18 if desired to facilitate lubrication of shafts 42 and 44 at times.

The protruding ends of shafts 42 and 44 from rear plug 40 are bent to form the contact arms 50 and 52 and spring means 54 and 56 (Fig. 11) connected respectively between arms 50 and 52 to the corresponding sides of member 30 within section 18 are placed to normally hold arms 50 and 52 in an upturned position where they are in a relative position as shown in Fig. 6. On the ends of shafts 42 and 44 which project from the forward plug 38 in member 30 there is integrally or separately formed the respective collar like support members 58 and 60 which are formed so that their relative position to each other corresponds to that of arms 50 and 52 as shown in Fig. 7 and also as can be determined from Fig. 2. Thus, it will be understood as arms 42 and 44 are rotated on their longitudinal axes, collars 58 and 60 will move away from and towards each other correspondingly to arms 50 and 52.

Collars 58 and 60 are each drilled in parallel alignment with the longitudinal axis of member 30 to slidably, rotatably receive the respective elongated resilient arm extension members 62 and 64 which may be secured therein by the respective set screws 66 and 68. The forward end portions of arm extensions 62 and 64 are each bent downwardly at approximately right angles indicated by the numerals 70 and 72 and the extreme outer ends thereof are then bent towards each other in a V-shape to form the supports 74 and 76 for the massaging tips 78. These tips are preferably made from soft plastic or surgical rubber but may of course be formed from any other suitable material and as shown I preferably shape them with a projecting tip or peak 80 that increases the effectiveness of interproximal stimulation in gingival massage. Tips 78 are frictionally placed on supports 74 and 76 and may be easily removed for cleaning and sterilizing. On the top side of each collar 58 and 60 I have placed a guide mark 82 and on each arm extension 62 and 64 there are a plurality of like calibrations or guide marks 84. This serves to align and adjust the relative positions of tips 78 and by having the marks 84 it is possible to adjust both extension arms alike by aligning the respective marks 84 with mark 82.

For rotating shafts 42 and 44 on their longitudinal axes so that tips 78 move toward and away from each other as will later be described in detail I use a small direct drive electric motor indicated generally by the numeral 86 in Fig. 5. This motor is of a type commercially available, except for certain adaptations I shall describe, and therefore the details of its construction, having no patentable significance as concerns this invention, are not described in detail. Particularly, I wish to point out that motor 86 is of the type having a rotating drive shaft 88 and is not a vibrating mechanism which is found in practically all other devices of this class. For purpose of this description the end of motor 86 from which shaft 88 projects is referred to as the rear face 90 (Fig. 5). To this face I have secured a plate 92 (Figs. 2 and 5) by means of screws or bolts and nuts 94 and this plate is provided with a suitable opening for the

projection of shaft 88 toward the rear. On plate 92 and at one side of shaft 88 is the bracket or support 96 to which the gear 98 is concentrically rotatably secured by any means such as nut 100 attached to shaft 99 which is flush with the left side of gear 98 as viewed in Fig. 5. Shaft 88 has been externally threaded and gear 98 has been associated therewith to form a worm gear for operation in a well known manner. At the other side of shaft 88, a bar 102 is disposed in a track means 104 integrally formed in plate 92 for a vertical sliding movement which is accomplished by a rigid link 106 pivotally connected at one end 108 to bar 102 and similarly eccentrically connected to gear 98 at the other end 110. By this arrangement it will be understood that rotation of gear 98 will cause bar 102 to travel alternately upwardly and downwardly in track 104 for a predetermined distance and at a fixed rate of speed which may be varied depending upon the diameter of gear 98 and/or the point of attachment thereto of link 106 relative to the axis of the gear. Across the bottom of bar 102 there is integrally formed or otherwise secured a cross member 112 which extends transversely of the longitudinal axis of member 30 and remains in this relative position throughout its vertical movement.

Motor 86 is pivotally mounted at its lower forward end to the upper forward portion of lower casing section 18 by means of the pin 114 (Figs. 1 and 2) and for this purpose I have mounted a bottom plate 116 to motor 86 for receiving pin 114. Thus mounted, cross member 112 will be positioned transversely of the arms 50 and 52 (Fig. 6) and will push against them in its downward movement so as to move them away from each other (Fig. 7) causing shafts 42 and 44 to rotate on their longitudinal axes. Springs 54 and 56 will of course return arms 50 and 52 to their position shown in Fig. 6 on the upward movement of cross member 112.

As pointed out above, motor 86 is mounted in lower section 18 to pivot on pin 114 and this has been designed to afford certain adjustments in the movement of tips 78 as follows. Bar 102 having a stroke of a predetermined distance, it will be understood that the farther above arms 50 and 52 cross member 112 is located relative to the position in Fig. 6, the less bar 102 will descend into section 18 to provide a correspondingly shorter path of travel of arms 50 and 52. Conversely, the closer bar 102 is to arms 50 and 52, the deeper into section 18 will be its descent and the greater the rotation of shafts 42 and 44. This of course directly affects the closeness which tips 78 approach each other. To accomplish this adjustment a screw member 118 depends from the top of the upper casing 16 and is rotated by a control knob 120. With section 16 in place over motor 86 and attached to lower section 18, screw 118 registers with an internally threaded opening 122 in the top of motor 86. Thus by turning screw 118 to take up the threads in opening 122 the rear of motor 86 will be elevated as it pivots on pin 114 and obviously raises the lowermost point to which bar 102 can descend. By reversing the movement of knob 120 the rear of motor 86 is lowered allowing bar 102 to penetrate deeper into the lower section 18. The upper housing section 16 has an opening 124 for access to the contact 126 to which the electric cord 128 is attached in a well known manner.

The speed at which bar 102 reciprocates or in other words the relative number of complete strokes per minute that it makes is one of the important characteristics that distinguishes this invention from others in the same class and is a factor which in cooperation with the manner of operation of tips 78 produces an entirely different effect and result from present type massaging devices. Such present type devices appear to depend upon high speed mechanical vibrating means to rock or shake or vibrate a massage arm or arms that in turn tap, hit or pummel the tissue in a manner which has mistakenly been referred to as a massage movement or treatment. Compared to

such devices, my massage apparatus might well be classified as a slow speed device for the rate of strokes per minute of bar 102 is materially slower than such rates on massage arms actuated by vibrating devices. Such other devices are known to tap or pummel the tissue at rates in the thousands per minute which as pointed out earlier does not permit the tissue to rebound due to its normal resiliency and consequently creates a static condition as affects circulation. Such rapid pounding of the tissue does not therefore accomplish the purpose and function of proper massage in the form of rhythmical compression and release which can be found defined in all literature on the subject.

With reference now to the use and operation of this device it will be noted when arms 50 and 52 are in upright position (Fig. 6) the tips 78 are oppositely disposed and at their widest point of separation. This spacing can be manually adjusted by loosening set screws 66 and 68 (Fig. 3), rotating shaft extensions 62 and 64 to move the tips 78 closer together and retightening the screws. In doing this, guide lines 82 and 84 make it possible to adjust each tip an equal amount and thus the spacing can be adapted for any width gums. When motor 86 is started and bar 102 reciprocates in a vertical plane, cross member 112 will push arms 50 and 52 as described to move tips 78 toward each other. In this operation, the upward position of arms 50 and 52 is such that they are normally inclined slightly away from the vertical and away from each other to assure their rotation as described. To further facilitate this action, the upper inner surface of each arm 50 and 52 may be beveled as at 130 for a sliding contact with cross member 112 in an obvious manner. On the upward stroke of bar 102, springs 54 and 56 will, of course, move the tips 78 away from each other. It will be appreciated that the movements of tips 78 are rhythmical and positive and as seen in Fig. 3 the movement of each tip defines a curved path first downwardly, then toward the opposite tip or toward the tissue being acted upon and then slightly upwardly. It is a smooth firm movement that gently compresses or kneads the tissue so as to be a distinct contrast from the staccato tapping of a vibrating mechanism and to simulate more naturally the massage movement of manual manipulation. Tips 78 can be placed to straddle the gums so that both sides are compressed and released simultaneously and can be moved back and forth and up and down as may be required with the points 80 working in the interproximal spaces.

Much experimenting has been done relative to the rate of speed at which the tips 78 move toward and away from each other and while I do not propose to limit this invention to any specific rate, I do wish to point out certain factors which are deemed to be of importance. I have found that compression of the gums by tips 78 at rates up to 300 times per minute produce much more beneficial results as compared with high speed vibrating devices that operate in the thousands per minute. Where the dividing line on speed is which separates a compression and release action from a constant tapping by vibration cannot be stated with any degree of certainty and therefore what I claim as the basic innovation in this invention is a device which departs from the vibrating principle and utilizes the compression and release approach for cooperation with the normal ability of the tissue to rebound from a gentle compression. In this respect, it has been established that the average pulse rate is around 70 per minute with variations of course both slower and faster under certain circumstances and therefore by adapting the speed of movement of tips 78 in some definite relationship to the pulse rate, the benefits of the massage are found to be highly beneficial. Thus, moving the tips for a compression action at a rate equal to half as much or two or three times the pulse rate has proven very satisfactory. A slower rate will of course retain the compression and release principle, and higher rates that do not get into a

vibrating action will still be of considerably greater benefit as compared with high speed vibrators.

The raising and lowering of the rear end of motor 86 by screw 118 (Fig. 2) previously described, affords another important adjustment that is novel in devices of this class. By lowering the motor 86, cross member 112 will descend deeper into casing section 18 and cause a greater rotation of shafts 42 and 44 by moving arms 50 and 52 as shown in Fig. 7. This of course moves tips 78 closer together than would a lesser rotation of shafts 42 and 44 and provides a positive, firm and more sustained compressing action. Because arms 50 and 52 cannot respond to springs 54 and 56 until cross member 112 moves upwardly, the action by tip 78 is definitely one of gentle but firm compression as distinguished from a tap or pummeling. This pressure is of course increased or decreased by initially adjusting the spacing of tips 78 as described.

Another innovation in this invention resides in the use of the resilient shaft extensions 62 and 64 which add yieldability in the action of tips 78. Thus, as the tips 78 press against the gums 132 (Fig. 1) a slight bending in the extensions 62 and 64 may occur in response to resistance by the gums to the pressure of tips 78. Thus there is a yieldingness to the compression action that makes the massage more gentle than if the massage tips were mounted to rigid members. Such yielding ability of members 62 and 64 can of course be increased or decreased as may seem appropriate by adjusting them longitudinally in collars 58 and 60.

With reference now to Fig. 12 I have shown my massaging device mounted on a vertically adjustable support 134 for use on parts of the body other than the gums and illustrated as being used on a leg 136. The structure of this device is the same as previously described so that like parts are given like numerals. However, in the case of the massage tips it may be preferable to use flat pad members 138 and the shaft extensions 62 and 64 may terminate in the bifurcated arms 140 and 142 which attach to opposite ends of the pads 138 as shown and thereby serve to make the pads conform to the contour of the portion being massaged. It is also pointed out that while two massaging pads are shown, it is possible to remove and pad and extension arm and use the remaining one when massaging such places as the small of the back, and the like.

It is submitted that the invention shown and described is aptly suited to achieve the purposes intended and is characterized by a combination of highly useful and mutually cooperating elements that combine their respective and proportionate functions in accomplishing the objects sought to be obtained.

Some changes may be made in the construction and arrangement of my massage apparatus without departing from the real spirit and purpose of my invention, and it is my intention to cover by my claims, any modified forms of structure or use of mechanical equivalents which may be reasonably included within their scope.

I claim:

1. A massage device, comprising, a housing, a shaft partially disposed in said housing and partially protruding therefrom, an arm on the inner end of said shaft, a massage member on the outer end thereof, an electric motor, a shaft driven by said motor a vertically reciprocating cross member operatively connected to said shaft, said motor pivotally secured at one end to one end of said housing so said cross member is spaced above and in line with said arm and capable of contacting the same in the downward stroke of its travel, said motor when actuated causing said cross member to bear against said arm to partially rotate said shaft in one direction about its longitudinal axis, means to partially rotate said shaft in the other direction when said cross member moves upwardly away from said arm, and means gearing said shaft to said motor so that the reciprocation of said cross

member is fixed to contact said arm at a rate synchronized with the ability of the tissue being massaged to rebound due to its normal resiliency after being compressed by the massage member.

2. A device as defined in claim 1 characterized by a manually rotatable screw means in said housing threadably connected to said electric motor whereby said electric motor can be selectively raised and lowered on its pivot point to different fixed positions within said housing and thereby vary the distance between said cross member and said arm to selectively change the duration of contact between the cross member and said arm during a given stroke of said cross member which correspondingly varies the degree of rotation of said shaft.

3. A device as defined in claim 1 characterized by a resilient shaft extension rotatably attached to the outer end of said shaft with said massage member on the outer end of said shaft extension, and means to fix said shaft at different positions of rotation relative to said shaft.

4. A massaging apparatus, comprising, a housing designed to serve as a handle means, a pair of parallel shafts disposed in said housing so as to project therefrom, a resilient shaft extension rotatably attached to the outer end of each shaft, massaging tips in spaced relationship to each other on the outer end of each shaft extension, means to fix said shaft extensions at different positions of rotation relative to said shaft whereby the spaced relationship of said tips can be adjustably fixed, an arm on the inner end of each shaft, a vertically reciprocating cross member in said housing positioned to contact said arms on its downward stroke, means in said housing for actuating said cross member, said cross member causing said shafts to partially rotate in one direction about their longitudinal axes so as to move said tips toward each other, means to rotate said shafts in the opposite direction, and said cross member constructed and arranged to operate at a rate whereby said tips produce a rhythmical compression and release or kneading movement of the body tissue to which it is applied and thus enables the tissue to rebound due to its normal resiliency after being compressed by said tips, and means within said housing to vary the distance between said cross member and said arms so as to selectively change the duration of contact between said cross member and said arms during a given stroke of said cross member which correspondingly varies the degree of rotation of said shafts.

5. A massaging device including a pair of shafts partially rotatable in two opposite directions respectively about their longitudinal axes, massage tips carried by said shafts and movable toward and away from each other by alternate directions of rotation of said shafts, an arm on one end of each shaft, a vertically reciprocating cross member positioned to contact said arms on its downward stroke, means for actuating said cross member, said cross member causing said shafts to partially rotate in one direction about their longitudinal axes, means to rotate said shafts in the opposite direction, and means to vary the distance between said cross member and said arms so as to selectively change the duration of contact between said cross member and said arms during a given stroke of said cross member which correspondingly varies the degree of rotation of said shafts.

6. A massaging apparatus, comprising a support, a pair of spaced parallel shafts mounted in said support for rotation about their longitudinal axes, a massage head on one end of each respective shaft, said massage heads oppositely disposed and in spaced relationship in starting position, an angularly disposed arm on the other end of each respective shaft, said arms in parallel spaced relationship defining their starting position, means movable into engagement with said arms in a rhythmic sequence to move them away from each other causing partial rotation of said shafts in one direction and a corresponding movement of said massage heads toward each other, means engageable with said arms to return them to starting posi-

tion, and means to selectively vary the duration of rhythmic contact between said arms and said arm engaging means.

7. A device as defined in claim 6 wherein said last two mentioned means are constructed and arranged to produce a gentle rhythmic movement of said massage heads toward and away from each other at a rate bearing some direct relationship to the average pulse rate in the human body.

8. A massage apparatus, comprising a support, a pair of spaced parallel shafts mounted in said support for rotation about their longitudinal axes, a massage head on one end of each respective shaft, said massage heads oppositely disposed and in spaced relationship in starting position, an angularly disposed arm on the other end of each respective shaft, said arms in parallel spaced relationship defining their starting position, a reciprocating bar member operatively associated with said support, means for reciprocating the same, said bar engageable with said arms for moving the same apart to cause partial rotation of said shafts and a corresponding movement of said massage heads towards each other, means engageable with said arms to return them to starting position, and means selectively varying the length of the stroke of said bar in reciprocating movement to selectively vary the duration of contact of said bar member with said arms and to correspondingly vary the degree of rotation of said shaft.

9. A massaging apparatus, comprising a support, a pair of spaced parallel shafts mounted in said support for rotation about their longitudinal axes, a massage head on one end of each respective shaft, said massage heads oppositely disposed and in spaced relationship in starting position, a motor driven reciprocating bar member, said bar member engageable with said arms for moving the same apart to cause partial rotation of said shafts and a corresponding movement of said massage heads towards each other, means engageable with said arms to return them to starting position, means selectively varying the length of the stroke of said bar in reciprocating movement to selectively vary the duration of contact of said bar with said arms and to correspondingly vary the degree of rotation of said shaft, and gearing on said motor to control the reciprocation of said bar at a rate by which the corresponding movement of said massage heads toward and away from each other can produce a gentle but firm rhythmic compression and release effect on tissue being massaged as distinguished from a rapid tapping and pummeling effect of a high speed vibrating device.

10. A massaging device including a pair of shafts partially rotatable in two opposite directions respectively about their longitudinal axes, massage tips carried by said shafts and movable toward and away from each other by alternate directions of rotation of said shafts, a reciprocating member operatively engageable with said shafts only during one direction of reciprocation and constructed so as to apply a relatively steady and firm force thereto to partially rotate them in one direction, means to rotate said shafts in the opposite direction, and means to selectively vary the duration of operable engagement between said reciprocating member and said shafts.

11. A massaging device including a pair of shafts partially rotatable in two opposite directions respectively about their longitudinal axes, massage tips carried by said shafts and movable toward and away from each other by alternate directions of rotation of said shafts, a force applying member operatively engageable with said shafts so as to apply a relatively steady and firm force thereto to partially rotate them in one direction, means to rotate said shafts in the opposite direction, and means to selectively vary the duration of application of force between said force applying member and said shafts.

12. A massage device, comprising, a housing having a lower and upper section, a shaft partially disposed in said lower section and partially protruding therefrom, an arm

on the inner end of said shaft, a massage member on the outer end thereof, an electric motor, a vertically reciprocating cross member operatively connected to said motor, said electric motor pivotally secured at one end to one end of said lower section so said cross member is spaced above and in line with said arm and capable of contacting the same in the downward stroke of its travel, said upper section attachable to said lower section to enclose said electric motor, said motor when actuated causing said cross member to bear against said arm to partially rotate said shaft in one direction about its longitudinal axis, means to partially rotate said shaft in the other direction when said cross member moves upwardly away from said arm, and a manually rotatable screw means in said upper section threadably connected with the top side of said electric motor whereby said electric motor can be selectively raised and lowered on its pivot point to different fixed positions within the lower section and thereby vary the distance between said cross member and said arm to selectively change the duration of contact between the cross member and said arm during a given stroke of said cross member which correspondingly varies the degree of rotation of said shaft.

13. A massage device, comprising, a housing having a lower and upper section, a shaft partially disposed in said

5
